UNITED STATES PATENT OFFICE.

GRANT LAMBRIGHT, OF FOND DU LAC, WISCONSIN.

DESIGN FOR A TIRE-TREAD.

58,243.

Specification for Design.

Patented June 28, 1921.

Application filed December 27, 1920. Serial No. 433,509. Term of patent 14 years.

To all whom it may concern:

Be it known that I, GRANT LAMBRIGHT, a citizen of the United States, residing at Fond du Lac, in the county of Fond du Lac and State of Wisconsin, have invented a new, original, and ornamental Design for a Tire-Tread, of which the following is a specification, reference being had to the accompanying drawing, forming part thereof.

Figure 1 is a face view of a section of a tire tread showing my new design, and

Fig. 2 is a fragmentary cross sectional view of the same, the section being indicated by line 2—2 of Fig. 1.

I claim:

The ornamental design for a tire-tread, as shown.

In testimony that I claim the foregoing I have hereunto set my hand at Fond du Lac, in the county of Fond du Lac and State of Wisconsin.

GRANT LAMBRIGHT.
